(57) **CLAIM**

The ornamental design for a radar apparatus for drone detection as shown and described.

DESCRIPTION

FIG. 1 is a perspective view as seen from the front side to back side of a radar apparatus for drone detection showing our new design,

FIG. 2 is a perspective view as seen from the back side to front side thereof,

FIG. 3 is a front elevational view thereof,

FIG. 4 is a rear elevational view thereof,

FIG. 5 is a left side elevational view thereof,

FIG. 6 is a right side elevational view thereof,

FIG. 7 is a top plan view thereof; and,

FIG. 8 is a bottom plan view thereof.
